UNITED STATES PATENT OFFICE.

DANIEL W. TROY, OF MONTGOMERY, ALABAMA.

METHOD AND APPARATUS FOR THEATRICAL PURPOSES.

1,025,338.

Specification of Letters Patent.

Patented May 7, 1912.

Application filed January 14, 1911. Serial No. 602,675.

To all whom it may concern:

Be it known that I, DANIEL W. TROY, a citizen of the United States, and a resident of the city and county of Montgomery, State 5 of Alabama, have invented certain new and useful Improvements in Methods and Apparatus for Theatrical Purposes, of which this is a specification, reference being had to the drawings forming part hereof.

10 The invention relates to theatrical and like effects produced by the light of fluorescence, and its objects are to provide novel and efficient methods and apparatus for the production of such effects.

15 In the drawing Figure 1 shows a general application of the invention, Figs. 2 to 7, inclusive show details of the application of fluorescent material, Fig. 8 illustrates the method and apparatus for exciting fluorescent 20 material so as to be visible through non-fluorescent material, and Fig. 9 shows a modified use of fluorescent material.

25 In general the invention is carried into effect by providing theatrical costumes, scenery, stage effects, and the like, composed wholly or in part of fluorescent material, and then exciting such material by a source of substantially ultra-violet light, such as an arc lamp screened by dark blue or violet 30 cobalt glass or an equivalent medium substantially opaque to visible light but substantially transparent to ultra-violet light.

35 The invention is further carried into effect by intermittently illuminating the costumes, etc., by ordinary and by substantially ultra-violet light; and also by illuminating fluorescent material, on the persons or costumes of performers, for example, covered by semi-transparent or translucent non-fluorescent 40 material such as lace, gauze, or other more or less open work textile fabric, thus obtaining a striking and novel effect of a luminous body visible through a partly opaque covering.

45 In applying the fluorescent material I may treat fabrics by immersion in a fluorescent solution, such as that of fluorescein, or of uranin, or of other substances of like qualities. When dried such fabrics are brilliantly luminous under strong ultra-violet 50 light excitation. I may, if desirable, otherwise incorporate in the fabric fluorescent material. I may apply to fabrics, scenery, stage effects and the like, fluorescent material in 55 the form of powder, or in granules, or crystals, employing a binder, such as size, glue,

varnish or the like. Efficient results can be had by employing uranium glass in the form of beads, spangles, and other ornaments, and attached as by sewing to fabrics, etc. While 60 there exist a considerable number of available fluorescent materials I prefer to employ one of the hydrocarbons such as fluorescein or uranin for treating fabric, owing to its simplicity of application and cheapness, and 65 to use uranium glass for spangles or ornaments, although the uranium sulfate in its ordinary commercial form is quite as brilliantly fluorescent and there are many other materials obtainable in the form of crystals 70 or powders, among them calcium tungstate, which are, perhaps, as desirable as uranium glass.

In Fig. 1, the source of illumination is shown as a "spotlight" projector, or arc 75 lamp 1, provided with a reflector (partly broken away in the figure) and normally screened by such a medium as deeply colored cobalt glass or other material substantially transparent to ultra-violet light but substantially opaque to ordinary light. A deeply colored cobalt glass is effective in practice but a combination of cobalt glass and some other material can be employed to advantage if the light transmitted is desired more 80 completely ultra-violet in character. In the figure such a screen is shown at 2 as a hinged front or cover to the projector. The source or sources of ultra-violet excitation may be disposed as in a balcony or gallery 3, or elsewhere. At 4 is a performer, standing on a stage 5, 6 and 6' being parts of scenery, and 7 a "back drop." Obviously, the fluorescent 85 material may be applied to any or all of the objects illuminated by the projector or projectors employed. As an example of the practical operation of the invention, the clothing of the performer may be assumed to be treated as described. An illumination with the unscreened projector discloses nothing unusual. As soon, however, as the ordinary illumination is discontinued and the fluorescent material illuminated by substantially ultra-violet light, which is done by interposing the screen 2 in front of the arc 90 light, the clothing becomes brilliantly visible against a practically dark background, particularly if the sole illumination of the stage is that afforded by the projector. It should be understood, however, that the fluorescence, especially under strong ultra-violet 95 excitation, is sufficiently brilliant to afford 100 105 110

more than passable effects even if the stage is at the same time illuminated by incandescent lamps, although the fluorescent material is, of course, more effective when it constitutes practically the sole source of stage illumination. This is especially true of the less brilliantly fluorescent materials, many of which are very inexpensive and give off fluorescent light of great beauty though less strongly than such substances as uranium glass, calcium tungstate, etc.

Fig. 2 shows a surface coating, 8', as applied with a binder to a sheet of fabric or other material, 8, where the fluorescent substance is powdered or granular as described.

Fig. 3 shows a button or spangle 13, of uranium glass or other suitable fluorescent material, attached by sewing at 13' to a fabric 12.

Fig. 4 shows a modified spangle at 11, provided with an eye 11' for attachment to fabric or other material.

Fig. 5 shows a detail of a net work, or bead work, fluorescent beads, 9, 9, etc., being shown strung on cords or threads 10, 10.

Fig. 6 shows a plurality of spangles, 11, 11, etc., attached to a fabric 12.

Fig. 7 shows a detail of a fringe of relatively long beads or cylinders, 9', 9', attached to cords 10', 10'.

Various other methods of attachment of fluorescent material are entirely obvious and need no description.

In Fig. 8 the application of the invention to the illumination of fluorescent material partly screened by non-fluorescent material is illustrated generally. On a stage or platform 14, is a performer 15, having a portion of her fluorescent costume, 16, covered by some such translucent material as the gauze or lace skirt and sleeves, 17, 17, 17. One spot-light projector is shown at 18, screened by a readily removable light-filter such as described with reference to Fig. 1. Beneath the stage may be another source of illumination, such as the projector 18', and a mirror for directing the light upward through the stage (which in this case must be provided either with a glass covered opening such as indicated in sectional view, or an open-work grating). The operation of the apparatus is obvious. In practice I have obtained effective results by illuminating the fluorescent material through the overlying non-fluorescent material, although in this case the degree of excitation is not the highest as a substantial portion of the ultra-violet light is stopped by the overlying material. The best results are to be had by an organization such as shown where as much as possible the ultra-violet excitation is had by unscreened illumination of the fluorescent material. Any fabric not materially denser than an average silk handkerchief allows sufficient ultra-violet light to pass to very effectively excite

such a material as uranium glass or uranium sulfate, if the arc employed is approximately equal in candlepower to that usually employed in moving picture apparatus, and the fluorescent light is quite brilliant enough to plainly show through the non-fluorescent covering.

It will be understood that a performer, or a plurality of performers, attired as described, may be first exhibited under the normal illumination, when the fluorescent phenomena will not be apparent, and then exhibited under the substantially ultra violet excitation; or the different illuminations can be alternated at will. The effects which may be had are sufficiently obvious.

In Fig. 9 I have shown a detail of the application of fluorescent material in the representation of a fire-fly, 19, which may be formed of uranium glass (or any other suitable substance) and attached to the clothing of performers, or exhibited as flying through the air (in such case suspended by a non-fluorescent support) or otherwise.

It will be understood that while the description has been principally directed to the treatment of costumes the invention is equally applicable to practically all stage paraphernalia. It will also be understood that the invention is not limited in application to objects displayed on a stage, since it may be employed in connection with outdoor representations such as parades, pageants, and the like.

Obviously the invention can be carried into effect with other sources of ultra-violet light than those described; among these, the various "uvol" lamps recently employed in producing substantially ultra-violet light for germicidal purposes; but for ordinary theatrical purposes I prefer to employ the ordinary arc lamps generally used and screen them with cobalt glass or some other suitable medium.

It is to be noted that while the invention employs the ultra-violet light as the exciting agent an illumination or excitation substantially ultra-violet is quite efficient and is very easily had.

Having described the invention, what I claim is:

1. The method described, consisting in successively directing upon fluorescent material overlaid in part by non-fluorescent material and carried by a performer, lights, one substantially ultra-violet in character and the other substantially visible in character, whereby first one and then the other of said materials is rendered principally visible, substantially as set forth.

2. The method described, consisting in successively directing, upon a costume composed in part of fluorescent material and in part of non-fluorescent material and carried by a performer, lights, one the greater por-

tion of which consists of ultra-violet rays, and another the greater portion of which consists of visible rays, whereby first one and then the other of said materials may be 5 rendered principally visible, substantially as set forth.

3. Apparatus of the class described, consisting of a theatrical costume composed in part of fluorescent material and in part of 10 non-fluorescent material, a source of light, and means for successively directing against said costume substantially visible and substantially ultra-violet light.

4. As means for theatrical display, a costume composed in part of fluorescent material and a source of substantially ultra-violet 15

light arranged to excite such material, substantially as set forth.

5. As means for theatrical display, a costume comprising an inner garment composed 20 in part of fluorescent material, and an outer garment of non-fluorescent material and of open work texture, and a source of substantially ultra-violet light arranged to excite such fluorescent material, substantially as set 25 forth.

Witness my hand this 11th day of January 1911.

DANIEL W. TROY.
